Attorney,

UNITED STATES PATENT OFFICE.

JOHN TÓTH, OF PHOENIXVILLE, PENNSYLVANIA.

RAILWAY-CROSSING GATE.

1,102,968.

Specification of Letters Patent.

Patented July 7, 1914.

Application filed October 7, 1913. Serial No. 793,834.

To all whom it may concern:

Be it known that I, JOHN TÓTH, a subject of the King of Hungary, residing at Phoenixville, in the county of Chester and State 5 of Pennsylvania, have invented certain new and useful Improvements in Railway-Crossing Gates, of which the following is a specification.

This invention relates to railway crossing gates.

The object of the invention is to provide a crossing gate which will be operated by an approaching train, in such manner that ample time will be afforded a person approaching the crossing to enable him to stop his team in time to avoid danger.

A further object is to provide a crossing gate which will be operated either by an approaching or a backing train, or by two trains going in opposite directions simultaneously, the arrangement of the parts being such that the actuation of one gate will not affect the other, the gate or gates being returned to normal position when the train 25 has reached the pre-determined distance therefrom.

With the above and other objects in view as will appear as the nature of the invention is better understood, the same consists in the 30 novel construction and combination of parts of a railway crossing gate as will be hereinafter fully described and claimed.

In the accompanying drawings forming a part of this specification and in which like characters of reference indicate corresponding parts: Figure 1 is a view in perspective of a section of a two track railway equipped with the gate of the present invention. Fig. 2 is a view in side elevation, showing the 35 manner in which the gates are actuated by an approaching train. Fig. 3 is a view in vertical longitudinal section through one pair of tracks, showing more particularly the connection between the engine actuated 40 mechanism and the gates. Fig. 4 is a vertical transverse sectional view taken at the gates. Fig. 5 is a view in end elevation, partly in section, showing more particularly the manner in which the engine actuated 45 mechanism is mounted in a box or casing disposed transversely of the tracks. Fig. 6 is a detail view in elevation, of the actuator for transmitting the power caused by the impact between the wheels of a locomotive 50 or car to the gates.

Referring to the drawings, R designates

two pairs of rails of the usual ordinary construction and S, the sleepers or ties, and as these parts may be of the usual or any preferred construction, further description is 60 deemed unnecessary.

It is designed that the tracks shall be divided up into sections or blocks of any desired length, and at the end of each block and extending transversely of the tracks is 65 a boxing or housing 1 which may be left open at its top or inclosed and may be constructed of any preferred material, such as wood, metal, or cement, as may be found preferable. Secured to the floor or base of 70 each of the casings are three standards 2, 3, and 4, the two standards 2 and 3 each carrying a single journal box 5, while the intermediate standard carries two journal boxes 6 and 7. These journal boxes are engaged 75 by two shafts 8 and 9, the outer ends of which project beyond the standards 2 and 3, and each has secured to it a grooved sheave 10 and 11. Rigidly secured on each of the shafts 8 and 9 are two disks 12 and 13, one 80 of which, in this instance, the disk 13 is shown in detail in Fig. 6. Each of the disks has within its periphery a channel or groove 14 in which is pivoted at 15 a dog 16 having its lower end 17 rounded and its 85 upper end provided with a right-angularly disposed lug or finger 18. Secured to the inner wall of the channel is a spring 19 that engages with the dog adjacent to its upper end and is designed to act as a buffer to absorb the initial shock resulting from the 90 contact of the wheel of a locomotive or car therewith. As clearly shown in Fig. 2, the dogs on the disks 12 normally occupy a vertical position when the gates are raised, 95 while the dogs on the disks 13 are disposed at an angle of approximately 45° to the first-named dogs. In addition to forming a means for effecting positive co-action between the dogs and the wheels of a locomotive or car, the fingers 18 also serve as stops to limit the downward throw of the dog as the finger will engage with the base of the rail when moved to the limit of its downward throw.

Arranged adjacent to the crossing C, and upon each side of the outer rails of the pair are two standards 20 that are bolted to a suitable base, not graphically illustrated, and are connected by a tubular brace 21 100 through which extends a shaft 22, journaled near its ends in the standards 20 and project-

ing beyond the same at each end, the projecting portions having secured to them grooved sheaves 23, the arrangement on each side of the crossing being the same. Arranged adjacent to the crossing are four standards or posts 24, the upper ends of which are slotted at 25, and in each slot is pivoted a gate arm, designated respectively, A, A', A², A³, each being of sufficient length 5 to span the crossing, and having at its lower end a counter-weight 26, thus to cause the gate practically to be balanced so that but small power will be required to shift it from a horizontal to a vertical position or vice 10 versa. Each shaft or pintle 27 of the gate arms carries on its outer end a grooved sheave 28, and passing around this sheave and the sheave 23 on each side of the track is a rope or chain 29.

20 The means for actuating the shafts 22 from either side of the track, thus to cause two transversely aligned gate arms to rise or lower simultaneously, consists of an endless chain or cable 30 which is passed once completely around the sheave 10 at the left hand end of the block and has its upper lead 31 passed downward and once around the right hand sheave 23, thence once around the right hand sheave 10 and thence back to the left hand sheave 10, from beneath. The reverse of this arrangement of the cable on the opposite side of the system is observed. Now, in operation, assuming the parts to be in the position shown in Fig. 1, and a train approaches in the direction of the arrow shown thereon, the forward pilot wheel will contact with the dog on the inner disk 12 of the right hand rails and partially rotate the shaft 8, and through the cable 30 rotate the 25 left hand sheave 10 and right hand sheave 23 and thus cause the gate arms A² and A³ to lower through the sheaves 28 and ropes 29, the movement of the shaft 8 at the opposite end of the section to that in which the 30 train is approaching being rocked at the same time through its sheave 10 and the cable 30 to bring the dog 18 on the disk 13 to position to be engaged by the forward pilot wheel of the locomotive when the engine 35 leaves the block, thus to cause the gates to rise. This operation also obtains when a train backs, or when two trains running in

opposite directions enter the block, in which case, the gates on both sides of the track will be closed and opened independent of each other. 55

The shock absorbing spring 19 is of great utility as without its employment, it would be practically impossible to operate the structure as the impact between the pilot 60 wheel and the dog would almost inevitably result either in a fracture of the latter or a breakage of the gates.

What is claimed as new is:—

The combination with two pairs of rail-way-crossing gates adapted to be disposed on opposite sides of a double-track road, each of said gates being adapted to move in unison with a corresponding gate located at the opposite side of the road, and means for opening and closing said gates by trains moving in either direction on each of said tracks, comprising a pair of continuous parallel shafts extending across both tracks, and supported in suitable bearings, a pair of 70 posts at each side of the road, a sheave mounted on each of said posts, sheaves on the ends of said parallel shafts, ropes connecting the post sheaves with the sheaves on the parallel shafts, a pair of horizontal 75 shafts at each side of the crossing, each of said shafts having mounted thereon two contact-devices adapted to be operated by a moving train, a sheave on the outer end of each of said horizontal shafts, a rope connecting said last-named sheave with the sheave on the parallel shaft located on the opposite side of the crossing, the said contact devices on each of said horizontal shafts being in angular relation to each other and 80 so disposed that a train moving in one direction closes the gates at each side of the road, through one of said contact devices before reaching the crossing, and opens the same 85 gates through the contact device on the opposite side of the crossing after passing the 90 crossing.

In testimony whereof I affix my signature in presence of two witnesses.

JOHN TÓTH.
